Primary Examiner — Paula Allen Greene(57) **CLAIM**

The ornamental design for pair of earbuds, as shown and described.

DESCRIPTION

FIG. 1 is a perspective view of pair of earbuds of the present invention;

FIG. 2 is another perspective view thereof;

FIG. 3 is yet another perspective view thereof;

FIG. 4 is a rear view thereof;

FIG. 5 is a front view thereof;

FIG. 6 is a top view thereof;

FIG. 7 is a bottom view thereof;

FIG. 8 is side view thereof; and,

FIG. 9 is another side view thereof.
